CLARENCE W. HUBBELL, OF NAUGATUCK, CONNECTICUT, ASSIGNOR TO THE GOOD-YEAR'S INDIA RUBBER GLOVE MFG. COMPANY, OF NAUGATUCK, CONNECTICUT, A CORPORATION OF CONNECTICUT

BATHING SHOE

Application filed August 8, 1928. Serial No. 298,165.

This invention relates in general to foot-wear and particularly to a bathing shoe.

One of the features of the invention is the provision of a cushion heel of soft resilient rubber composition intermediate the insole and outsole which latter completely covers the sole, arch, and the heel portions. It is the preferred practice in this invention to complete the building of substantially all portions of the shoe before the heel and the outsole are applied. The heel may be made of scrap rubber composition providing the required cushioning qualities, subjected to a semi-cure preferably, and then covered around its sides and corners with friction cloth after which a trim of a color, preferably contrasting with that of the upper, is applied over the friction cloth. The heel is then cemented to the upper and the insole, a foxing strip put on covering the joint of the heel to the upper and then the outsole put on completely covering the sole, the arch and the heel, after which all parts of the assembled shoe are vulcanized together to form an integral unitary article.

Another feature of the invention is the provision of a cushion heel of the foregoing character having a breast portion bevelled throughout the width of the heel.

Other features and advantages will appear as the description proceeds.

In the accompanying drawing, which is a side view of a bathing shoe embodying the invention, with the heel portions of the shoe broken away, the numeral 10 represents generally the upper of the shoe, the bottom edge being turned inward as indicated at 11 beneath an insole 12 having a cloth lining 13.

In the manufacture of the shoe, it is preferred practice to complete substantially all portions thereof before the heel and outsole are applied. This preliminary building includes joining the two counter portions of the upper 10 at the back of the shoe and cementing the edge portions 11 to the under margins of the insole 12. The heel designated 14 is composed of any suitable rubber composition such as scrap rubber, possessing the desired cushioning qualities and is characterized by a breast portion 15, preferably

bevelled from side to side of the heel. After subjecting the heel to a semi cure, which is the preferable practice, it is covered around its sides and corners with friction cloth, as indicated by the heavy line 16, a trim 17 of 55 gum usually contrasting with that of the upper is then applied over the friction cloth around the faces of the heel and the corners thereof, and the heel then cemented to the insole 12 and the inwardly turned edge portions 11 of the upper 10, after which a foxing strip 18 is applied around the joint of the top edge of the covered heel and the adjacent portions of the upper 10, to more securely join the heel to the shoe. The trim 17 60 covers the cushion heel 14 from view and provides a more satisfactory foundation for joining the edges of the heel to the insole and receiving the foxing strip 18 than would be afforded by the cushion heel alone. An outsole 19 is next applied to the bottom of the shoe so as to completely cover the sole portion, the arch, and the heel 14, the outsole partaking of the inclination of the bevelled breast portion 15, thus providing a one piece 65 covering over the entire bottom portion of the shoe. The assembled shoe is then cured, whereby the parts of the shoe are all vulcanized together to produce an integral unitary article. The sides and rear portion of the cushion heel 14 are preferably inclined outward toward the bottom edge, as indicated at 20 to an extent approximating $\frac{1}{16}$ ", so that when viewing the shoe from the side, the back wall of the heel inclines in the same 70 general direction as the bevelled breast portion 15.

The article of footwear thus produced is simple in construction, inexpensive to manufacture, presents an attractive appearance, and is in other ways a more comfortable and satisfactory bathing shoe than produced heretofore.

For an understanding of the scope of the invention, reference is to be had to the following claim.

Having thus described my invention, what I claim and desire to protect by Letters Patent is:

A bathing shoe of rubber composition in-

cluding an upper, an insole, a heel of soft rubber composition secured to the insole, said heel having a breast bevelled throughout its width, an outsole covering the bottom of the sole, arch, and heel, a trim of rubber composition enclosing the side and rear portions of the heel between the upper and the outsole, and a strip of rubber composition extending around the top of the trim between opposite corners of the breast and covering the adjoining portions of the trim and the upper, all of the parts being vulcanized together to form a unit.

Signed at Naugatuck, county of New Haven, State of Connecticut, this 3rd day of August, 1928.

CLARENCE W. HUBBELL.
